UNITED STATES PATENT OFFICE.

ALEXANDER D. FISHER, OF TORONTO, ONTARIO, CANADA.

TUBULAR CONFECTION.

Application filed May 29, 1925. Serial No. 33,723.

To all whom it may concern:

Be it known that I, ALEXANDER D. FISHER, of the city of Toronto, in the county of York, Province of Ontario, Canada, a subject of the King of Great Britain, have invented certain new and useful Improvements in Tubular Confections, of which the following is a specification.

In my prior Patent No. 1,484,016, dated Feb. 19th, 1924, I have shown and described a tube formed of compressed chocolate which was to be filled with a suitable fondant or other suitable filling and sealed at each end with a plug of chocolate.

The filling and plugging of the tubes presents no difficulty if the time element be disregarded but great difficulty is experienced in getting sufficiently rapid production to compete successfully with the chocolate bar for its particular market.

The requirements for rapid production are:

1st. That the plugging operations should be performed simultaneously on a large number of tubes;

2nd. That the bottoms of the empty tubes should be plugged without spoiling the true cylindrical surfaces of the tubes either internally or externally;

3rd. That the other ends of the tubes after filling should be plugged without spoiling the true cylindrical external form of the confection whether the filling material completely fills the tube or not; and

4th. That filling should be effected without depositing any filling material on the outside of the tube.

The above requirements are fulfilled by proceeding in the following manner. The tubes are placed and accurately centered in a vertical position on a form adapted to hold a convenient number, say one dozen. The tubes rest on dipping paper or a non-adhesive metal surface suitably held and positioned on the form. The form is taken to a machine adapted to drop melted chocolate in drops of a predetermined size and provided with depending dropping nozzles adapted to extend nearly to the bottoms of the tubes. A drop is thus deposited in the bottom of each tube sufficient to seal it and this is done without any being deposited on the inner cylindrical surface of the tube as happens if one attempts to drop the sealing material from the top of the tube.

The tubes, when the plugs have set, are

taken to the filling machine which is adapted to force fondant or other semi-liquid or plastic material in measured quantities through cylindrical nozzles of such a size that the chocolate tubes will fit over them easily but snugly. When the machine is in operation and a tube is in position on a filling nozzle the outflowing fondant presses back the tube as it emerges from the nozzle and at the instant the tube is substantially full it is removed with a quick partly side-wise movement to break the flow of fondant and another tube slipped in position, or the fondant may be cut mechanically.

The filling of the tubes thus being from the bottoms upwards, I ensure the tubes being completely filled at all points of their length, whereas, if it be attempted to fill them from the open end, unfilled spaces are very apt to be left at different parts of the length of the tubes and more particularly adjacent their bottoms. To ensure the proper outward expansion of the fondant against the inner walls of the tubes, a yielding pressure is maintained against the outer end of each tube until it is filled.

In view of the method of filling employed, the importance of having true inside cylindrical surfaces for the tubes will be appreciated. As already stated, to ensure complete and proper filling the chocolate tubes have a piston-like fit on the filler nozzles so that they are forced back as filled without any fondant flowing out between the adjacent cylindrical surfaces of the tubes and nozzles.

If then any tubes have had any plugging material dropped on their interior cylindrical surfaces, they will not fit on the nozzles but will split which will not only necessitate their being scrapped but will also upset the working of the filling machine and cause a waste of fondant.

The next step in the process is to partly apply the wrapper to the filled tube. The wrapping operator rolls the wrappers on the tubes and folds in the bottom ends only leaving the wrapper projecting in tubular form round the unplugged ends of the tubes. The partly wrapped tubes are again placed on a centering form adapted to carry, say, a dozen tubes and the form is taken to a dropping machine of the type employed in plugging the bottoms of the tubes, though short nozzles only are necessary. This machine deposits melted chocolate in drops of

sufficient size to seal the open ends of the tubes. The plugs so formed possess a true cylindrical outer form with a flat end, since the wrapper of a tube forms a cylindrical 5 mold wall in exact continuation of the outer surface of the tube and the chocolate, being in melted condition and the tube vertical, sets with a horizontal upper surface. When the plugs have set the ends of the wrappers 10 are folded down and the tubular confections are ready for packing.

The final result is that the wrapped confection has a true cylindrical form with substantially plane ends exactly at right 15 angles to the ends of the tube, which condition is necessary to give the confection the neat, attractive appearance necessary to please a fastidious public taste.

The accompanying drawings illustrate the 20 different stages of the process and also, diagrammatically, the apparatus employed.

Fig. 1 is a longitudinal section of a chocolate tube showing the nozzle of a dropping machine depositing plugging material in the 25 lower end;

Fig. 2 a similar view illustrating the filling of a plugged tube;

Fig. 3 a similar view of a filled and partly wrapped tube showing the nozzle of a dropping machine depositing plugging material 30 on the open end;

Fig. 4 a similar view of the complete confection with the wrapper removed;

Fig. 5 a plan view of a tube carrying and 35 centering form, partly broken away;

Fig. 6 a diagrammatical vertical section of a dropping machine;

Fig. 7 a similar view of a filling machine; and

Fig. 8 a perspective view of a completely 40 wrapped tube.

In the drawings like numerals of reference indicate corresponding parts in the different figures.

In Fig. 5 I show the form in which the tubular shells are placed ready for plugging and filling. This comprises a base 1 on which is secured a corrugated strip 2 of metal for forming V-shaped recesses in 50 which the lower ends of the tubes are received and in which they are held by the bar 3 carried by arms 4 pivotally connected with the ends of the base. The corrugations are, of course, formed so the tubes are accurately aligned and evenly spaced. Before the tubes are placed in position a strip 5 of confectionery dipping paper is slipped into position on the base, its forward edge being held under a metal strip 6. A strip of 55 polished metal to which chocolate will not adhere may be substituted for the dipping paper. The base may be of any length, but is preferably adapted to carry twelve tubes.

The form carrying the tubes is now carried to a dropping machine, such as shown

in Fig. 6. This machine is provided with a vertically movable platform 7 provided with operating means including a lever 8. Chocolate or other plugging material is placed in a container 9 provided with a hot 70 water jacket 10, which maintains it in melted condition. Connected with the underside of the container is a cylinder 11, in which operates a plunger 12.

From the lower end of the cylinder extends 75 a dropping tube 13, which should be long enough, when the platform 1 is elevated, to reach nearly to the bottom of a chocolate tube. The stroke of the plunger is adjusted so that by its rise and fall a predetermined quantity of chocolate is forced 80 through the tube 13. The plunger is usually a loose fit in the cylinder so that heated chocolate may flow past it, thus avoiding the necessity of employing valves. Crank and pitman mechanism 14 serves to operate the plunger. A dropping tube with its associated mechanism is provided for each of the chocolate tubes positioned in the form.

The form, having been placed on the platform, the latter is elevated so that the lower end of each dropping tube is close to the bottom of the chocolate tube in which it is positioned. The plungers are then reciprocated and the drop of melted chocolate 85 dropped into the bottom of the tube, perfectly sealing the same. The platform is then lowered and the form with the tubes removed. The tubes are allowed to stand a sufficient length of time for the chocolate plugs to solidify, and then are taken to the filling machine, which is illustrated diagrammatically in Fig. 7. Two feed rollers 90 15 feed the fondant or other filling to a rotary tubular valve 16. When the valve is in the position shown in Fig. 7, it closes off the inlet to a filling nozzle 17, on which, as hereinbefore referred to, a chocolate tube is fitted. The valve is then rotated, closing off 100 the flow of filling material from the feed rollers and opening up a communication between the filling nozzle and the cylinder 18 in which reciprocates a plunger 19. The plunger is forced towards the filling tube a sufficient distance to eject from the filling 105 tube a sufficient quantity of filling material to exactly fill the chocolate tube, which is then removed as hereinbefore referred to. The flow of filling is at this time again closed off by the rotation of the tubular valve and a fresh supply of fondant forced 110 into the valve and cylinder by the feed rollers. The filling tubes are then partly wrapped as hereinbefore described and again carried to the dropping machine, which may be the same dropping machine as used for plugging the bottoms of the tubes, though preferably a duplicate is employed. By this machine the sealing plug for the 115 upper end of each tube is deposited as here-

120 125 130

inbefore described and the completed confection is then ready for the completion of the wrapping operation, the completely wrapped confection being shown in Fig. 8
5 of the drawings.

What I claim is:—

1. In a process of forming a tubular confection the steps which consist in forming a chocolate tube, sealing one end by supporting the tube in a vertical position on a plane surface and dropping plastic plugging material to close the bottom of the tube from a point within the tube close to the bottom.
- 10 2. In a process of forming a tubular confection the steps which consist in forming a chocolate tube, sealing one end, filling the tube with filling material; partly wrapping the tube and leaving the wrapper extended 20 in tubular form about the open end; dropping melted plugging material into the mold formed by the projecting end of the wrapper and the end of the tube with its filling; and finally folding in the projecting 25 end of the wrapper.
- 15 3. In a process of forming a tubular confection the steps which consist in forming a chocolate tube, sealing one end by supporting the tube in a vertical position on a

plane surface and dropping plaster plugging material to close the bottom of the tube from a point within the tube close to the bottom, positioning the tube on a filling nozzle on which it has a piston-like fit, forcing filling material through the nozzle till the tube is filled and forced back to a position for removal, partly wrapping the tube and leaving the wrapper extended in tubular form about the open end; and dropping plastic plugging material into the mold formed by the projecting end of the wrapper and the end of the tube with its filling.

4. In a process of forming a tubular confection the steps which consist in forming a chocolate tube, sealing one end, positioning the tube on a filling nozzle on which it has a piston-like fit and forcing filling material through the nozzle till the tube is filled and forced back to a position for removal, partly wrapping the tube and leaving the wrapper extended in tubular form about the open end; and dropping melted plugging material into the mold formed by the projecting end of the wrapper and the end of the tube with its filling.

Signed at Toronto, Canada, this 19th day of May, 1925.

ALEXANDER D. FISHER.
